United States Patent Office

Des. 218,715

Patented Sept. 15, 1970

218,715

CALCULATOR OR SIMILAR ARTICLE

Edward E. Salter, Fairport, and Hugh M. Lee and Lewis W. Bennett, Rochester, N.Y., assignors to The Singer Company, a corporation of New Jersey

Filed Mar. 3, 1969, Ser. No. 15,984

Term of patent 14 years

Int. Cl. D18—01

U.S. Cl. D64—11

Fig. 1

Fig. 2

Fig. 3

FIG. 1 is a front perspective view of a calculator or similar article embodying our new design;

FIG. 2 is a top plan view thereof; and

FIG. 3 is a rear perspective view thereof.

FIGS. 1 and 3 show the appearance of the left side of the calculator or similar article. The right side is substantially similar in appearance to the left side of the calculator or similar article as presented.

We claim:

The ornamental design for a calculator or similar article, substantially as shown and described.
